CLAIM

The ornamental design for a hanger, as shown and described.

DESCRIPTION

FIG. 1 is a front elevation of the hanger showing my new design;

FIG. 2 is a top view thereof;

FIG. 3 is a side view as seen from the left of FIG. 1;

FIG. 4 is a side view as seen from the right of FIG. 1;

FIG. 5 is a bottom view thereof; and

FIG. 6 is an enlarged cross-section as seen from line 6—6 of FIG. 1.
